UNITED STATES PATENT OFFICE

2,327,143

MEANS FOR UPHOLSTERING FURNITURE

Paul Stadtler, Flushing, N. Y., assignor to Never-sag Products, Inc., Flushing, N. Y., a corporation of New York

Application July 22, 1941, Serial No. 403,545

8 Claims. (Cl. 254—79)

This invention relates generally to the upholstering of furniture and more particularly it relates to tools for use in applying lacing strips to furniture.

More specifically it relates to a tool for stretching and for holding stretched a lacing strip while it is being attached to the furniture frame, and coordinately therewith it relates to a tool for use in seating the furniture springs on the lacing strips.

The general objects of my invention are the provision of simple and effective tools for applying lacing strips to furniture.

Among the more particular objects of my invention are the provision for use in applying lacing strips to furniture of a tool for stretching a lacing strip and for holding it stretched while the lacing strip is being attached to a piece of furniture, the provision of a tool for use with either flat or recessed furniture frames to stretch lacing strips to be applied thereto, the provision of a tool for stretching a lacing strip by the application of a force that may differ in direction and in magnitude from the direction of the stretching force, and further the provision of a tool for stretching lacing strips that may be controlled by the body, leaving the hands free for all operations other than stretching.

These objects and such other objects as will hereinafter appear or be pointed out, are attained in the illustrative embodiments of my invention shown in the drawings, in which:

Figure 1 is a top plan view of a tool for stretching lacing strips, constructed in accordance with my invention;

Figure 2 is a bottom plan view thereof;

Figure 3 is a section on the broken line 3—3 of Figure 1, looking in the direction of the arrows, and showing a pin associated with the tool;

Figure 4 is a fragmentary elevational view of one end of the tool of Figure 1;

Figure 5 is a fragmentary sectional view substantially on the line 5—5 of Figure 3, looking in the direction of the arrows;

Figure 6 is a perspective view of a portion of the gripping head of the tool;

Figures 7 and 8 are respectively plan and elevational views showing one manner of using my improved lacing stretcher, this manner being particularly adapted for furniture having a flat frame;

Figures 9 and 10 are respectively plan and elevational views illustrating another manner of using my improved stretcher, this manner being

particularly adapted for furniture having a recessed frame; and

Figures 11 and 12 are respectively elevational and plan views of an improved tool for manipulating furniture springs in the operations associated with the application of lacing strips to furniture and the seating of said springs on the lacing strips.

In attaching lacing strips of the character described in the U. S. Patent #1,982,030, it is customary to fasten the end of a lacing strip to one side of the furniture frame as by nailing it thereto, and thereafter secure another portion of the lacing strip to the opposite side of the furniture frame and cut off the excess portion. The lacing strip thus applied must be given a tension before it is secured so that it will support the springs which rest on it, and through which pressure from the furniture seat is transmitted to the lacing strip. Since the fastening must take place while the lacing strip is under tension, it will be obvious that it is highly inconvenient if not impossible for a single operator to use his hands both for tensioning and for attaching the lacing strip to the furniture frame. By the use of my improved tool, however, the tensioning is effected by portions of the operator's body entirely independently of his hands thereby leaving his hands free for the attaching operation.

My improved lacing stretcher in the illustrative embodiment shown by way of example in Figures 1, 2 and 3 is designated generally by A and comprises a handle 10 having a head or body 11 from which spring a pair of legs 12 and 13. The handle is made of any suitable or preferred material, the qualities desired in such material being rigidity, strength and lightness. In the practical application of my invention I have found wood to be satisfactory for this purpose.

The head portion 11 of the handle 10 is preferably made of sufficient thickness to perform its function as will hereinafter be described. Where the handle is made of wood or similar material such thickening is conveniently effected by attaching a block 14 to the head portion 11, which has the effect of thickening this portion without at the same time thickening the leg portions 12 and 13, in which thickness is not needed. The block 14 may be attached to the handle 10 in any suitable or preferred manner such as by screws 15.

The end portions of the head 11 and the block 14 are rounded, as indicated at 16, and this rounding is conveniently contoured substantially along a circular arc or arcs, as shown in the drawings, in which also the block 14 is shown by

way of example as of flattened cylindrical form. A padding 17, which is preferably of tough, durable, compressible cushioning material such as reinforced sheet rubber or leather, is shown applied over the surface 16 and secured in place in any suitable or preferred manner, as by nails 17a. In order to improve the proper functioning of the tool, as will be described hereinafter, the padding 17 may also have an overhanging lower portion or apron 18 which extends beyond the block 14.

A lacing strip gripping device B is shown carried by what may be termed the upper surface of the tool and this device is shown as comprising a base block 19 (see Figures 5, 6), to which is pivotally secured, as by a pin 20, a gripping member or jaw 21, both the jaw and the base block being provided with complementary portions adapted to coact to grip the lacing strip.

The base block 19, which is shown in perspective in Figure 6, is provided in its illustrative embodiment, with a base plate 22 having a transverse rib 23 thereon. The rib 23 is interrupted, as shown at 24 to permit the accommodation thereover of portions of the lacing strip, where this has a configuration such as indicated in broken lines at K in Figures 4 and 6.

At one side of the base plate 22 is shown an upstanding wall 26 from which projects a lug 27 that overhangs the plate 22 and is provided with a recess 28.

The jaw 21 has an extension 29 that is adapted to fit into the recess 28, and it is pivotally mounted on the lug 27 by the aforesaid pin 20 which passes through a bore or bores 30 in the lug, and a bore 31 in the jaw 21. The extension 29 is cut away at its end portion so as to provide a space within which is positioned resilient means, such as a coil spring 32, this means seating in the recess 28 and serving to urge the extension 29 away from the lug 27, whereby the body portion of the jaw 21 is urged towards the plate 22, and whereby ribs or corrugations 33 on the jaw, which are complementary to the rib 23 of the plate 22 and to the ribs and valleys of the lacing strip, serve to grip the said strip securely, this gripping action being made automatic by the action of spring 32.

In Figure 4, I have indicated the manner in which the device B, just described, grips a lacing strip K. In Figure 3, I have shown the jaw 21 in full lines in its gripping position and in broken lines in a raised position in which it does not engage the lacing strip, so that the latter may be removed from the gripping device B by raising it from its seat on the plate 22.

At 34, I have shown ribs provided on the under surface of plate 22 for the purpose of biting into the wood of the handle and holding the plate against turning when it is secured to the handle. For the purpose of so securing it, I have shown, by way of example, a screw 35, which passes through the handle 10 and into a threaded bore 36 in the plate 22.

In each of the legs 12 and 13 is provided a set of spaced openings 45 and 46 into each of which may be inserted a pin 44 for a purpose that will presently appear. The pin 44 preferably fits snugly into the openings and is of such length as to project beyond the surface of the tool as appears from Figures 3 and 10. Each leg 12 and 13 is provided at its extreme end portion with a surface, such as 47 and 48, contoured so as to be adapted to engage the front portion of the waist of an operator. When the operator places

the tool against his body so that the tool projects forwardly therefrom, with the surfaces 47 and 48 pressing against his body, the gripping means B is adapted to receive the free ends of the lacing strip and may be tensioned by movements of the operator's body, and as will be explained subsequently, while his hands are at the same time free to perform the cutting and nailing operation. As will also appear hereinafter the space 49 between the legs 12 and 13 of the stretching tool may serve the purpose of permitting the nailing operation therewithin.

In Figures 7 and 8, I have attempted to illustrate the operation of applying a lacing strip L to a flat furniture frame F. The lacing strip L is shown having one end thereof nailed in place on the furniture frame F, as shown at 50. The lacing strip gripping device B is shown engaging a portion of the lacing strip, and it will be observed that the tool A is in such a position that the padding 17 on its end portions engages the side of the frame F. Due to the curved contour of said padding the tool may be rocked about its point of contact with the furniture frame laterally as well as up and down. To effect such rocking it is merely necessary for the operator to sway his body from side to side or to move it up and down, and the hands of the operator are at all times free to carry on the operation of nailing or other required operations. It will be observed that the tension on the lacing strip may be either increased or decreased in accordance with the direction of movement of the operator's body.

In the operation of applying the lacing strip L to the furniture frame F, the strip will first have its free end attached to the frame as at 50, and will then be gripped by the device B with the tool in such a position that there is no tension on the strip L. Such a position may be attained by placing the end of the tool in contact with the side of the furniture frame in a position in which it is angled upwardly and, if desired, also angled laterally. On straightening out the tool as by moving it from the dot and dash line position of Figure 7 to the full line position therein, tension may be applied to the strip L and still more tension may be applied by moving it from the upper dot and dash line position of Figure 8 to the lower dot and dash line position in the same figure. When sufficient tension has been applied the operator drives nails through the lacing strip and into the furniture frame at the point 51 and thereafter cuts off the strip to the required length.

In Figures 9 and 10, the operation of fastening a lacing strip M to a recessed furniture frame G is shown. One end of the lacing strip is nailed in place in the recess R of the frame G as indicated at 52, and the lacing strip is gripped by the device B of the tool A, as before. However, it will be observed that in Figures 8 and 10, the tool is used in an inverted position, as contrasted with Figures 7 and 8, and with the gripping device B positioned inside the frame instead of outside of it. The tensioning is effected by inserting a pair of pins 44 into the openings 45, 46 of the tool while the tool is in an upwardly angled position as shown in Figure 10. On moving the tool from the dot and dash line position of Figure 10 into the full line position of said figure, tension will be applied to the strip M. This tension may be increased by lateral angling of the tool about one of the pins 44, this being effected by moving the body laterally as in Figure 9. Assuming that the tilting has been effected

about a pin 44 in the lower leg 13 in Figure 9, as indicated by the broken lines, it will be observed that a pin 44 in the leg 12, on the completion of the angling movement as shown therein, will have moved away from the engagement with the side of the furniture frame. If the angling movement is sufficiently great the upper pin 44 may be withdrawn from the tool and put into the next one of the holes 45, as indicated in the full line position, whereby the tool will be prevented from returning to the broken line position of Figure 9. By alternating the angling between the legs 12 and 13, any desired degree of tension may be imparted to the lacing strip M.

It will be understood from this description that the lacing strip is conveniently tensioned by manipulation such as described. When sufficient tension has been applied the nailing operation is performed as indicated at 53, the strip having previously been cut to the requisite length.

It will be observed that the space 49 between the legs 12 and 13 of the tool is so situated that the nailing operation just mentioned may be effected therewithin.

The lacing strip serves as a seat for furniture springs, each of which seats on a pair of lacing strips crossing each other at an angle, usually a right angle. (See U. S. Patent #1,982,030.) In order to secure such seating easily and conveniently I may use a tool T, an illustrative embodiment of which is shown in Figures 11 and 12. This tool comprises an elongated handle portion 70 carrying a pin 71 at one end thereof, this pin having its free end 72 offset axially from the handle 70, while its inner portion extends angularly into the handle. The end 72 may be inserted into openings or may engage and bend portions of the furniture springs.

A groove 74 is shown in the illustrative embodiment of Figures 11 and 12 as extending transversely across the handle 70 adjacent one end of the tool T and it will be observed that it is situated at the same end as the pin 71. This groove 74 opens laterally as shown at 75 so that intermediate portions of a furniture spring may be inserted thereinto and then manipulated by movement of the tool. A closed bore 77 is also provided in the tool and this is adapted to receive an end of a furniture spring. This bore is conveniently located, as shown in the drawings, adjacent the groove 74.

At the other end of the tool is shown a transverse bore 76 which may be used to receive an end of a furniture spring and will permit the tool to slide to intermediate portions of the spring.

Further description of the use of the tool shown in Figures 11 and 12 is believed to be unnecessary as its use will be obvious to those skilled in the art.

While I have herein shown and described several illustrative embodiments of my invention and explained their use, it will be understood that my invention may be embodied in many other forms without departing from the spirit thereof, as will be obvious to those skilled in the art. It will further be understood that the disclosures herein are by way of illustration merely and are not to be interpreted in a limiting sense, and that I do not limit myself other than as called for by the prior art.

Having thus described my invention and illustrated its use, what I claim as new and desire to secure by Letters Patent, is:

1. In a tool for stretching lacing strips when applying them to furniture, a head provided

with a portion adapted to engage a furniture frame and to be rockable thereon, means for engaging a lacing strip carried by said head, a pair of spaced legs extending from said head, said legs being provided with surfaces adapted to be engaged by a portion of the body of an operator, whereby said operator may rock said tool and move said lacing strip engaging means so as to stretch the lacing strip.

10 2. In a tool for stretching lacing strips when applying them to furniture, means for engaging a lacing strip, means adapted for engagement by the body of an operator, and means intermediate said lacing strip engaging means and said body engaging means for contacting a furniture frame and serving as a fulcrum about which said tool may be angled when said body engaging means is moved.

15 3. In a tool for stretching lacing strips when applying them to furniture, means for engaging a lacing strip, means adapted for engagement by the body of an operator, and means intermediate said lacing strip engaging means and said body engaging means for contacting a furniture frame and serving as a fulcrum about

20 which said tool may be angled when said body engaging means is moved, said furniture frame contacting means being in the form of a pair of pins and a plurality of seats for each of said pins on said tool in each of which seats a pin may be removably received, and the seats for one pin being laterally spaced from the seats for the other pin.

25 4. In a tool of the character set forth in claim 1, a series of spaced openings in each of said legs into which a pin may be inserted, such pin when inserted being adapted to engage the side of a furniture frame and to act as a fulcrum about which the tool may be angled.

30 5. In a tool of the character set forth in claim 1, means carried by each of said legs at an intermediate portion thereof adapted to engage a furniture frame and to serve as a fulcrum about which said tool may be angled.

35 45 6. In a tool for stretching a lacing strip, means for gripping a lacing strip, a plurality of means at one end of said tool adapted to engage the furniture frame and to serve as a fulcrum about which the tool may be angled, and means at the other end of the tool for engagement by the body for angling said tool about said fulcrum by movement of the body, and means intermediate said first named means and said last named means to engage the frame of recessed furniture and serve to fulcrum the tool for stretching by movement of the body.

50 55 7. A tool for stretching furniture lacing strips during the process of applying them to furniture, said tool comprising a convexly contoured head, a lacing strip gripping device mounted on said head, and a pair of legs extending in spaced parallel direction from said head and each provided with surfaces adapted to seat on the waist of an operator.

60 65 8. In a tool for stretching lacing strips when applying them to furniture, a head provided with a portion adapted to engage a furniture frame and to be rockable thereon, means for engaging a lacing strip carried by said head, said head being provided with surfaces adapted to be engaged by a portion of the body of an operator, whereby said operator may rock said tool and move said lacing strip engaging means so as to stretch the lacing strip.
